CLAIM

The ornamental design for a chew toy for animals, as shown and described.

DESCRIPTION

FIG. 1 is a perspective view of a chew toy for animals showing my new design;

FIG. 2 is a right side view thereof, the left side is identical;

FIG. 3 is a perspective view thereof;

FIG. 4 is a front view of FIG. 3;

FIG. 5 is a rear view of FIG. 3; and,

FIG. 6 is a right side view of FIG. 3, the left side is identical.

The broken lines are for illustrative purposes only and form no part of the claimed design.
